UNITED STATES PATENT OFFICE.

JULIUS A. LANDSBERGER, OF ALAMEDA, CALIFORNIA.

CLOSURE FOR RECEPTACLES.

SPECIFICATION forming part of Letters Patent No. 731,793, dated June 23, 1903.

Application filed October 15, 1902. Serial No. 127,388. (No model.)

To all whom it may concern

Be it known that I, JULIUS A. LANDSBERGER, a citizen of the United States, residing at Alameda, in the county of Alameda and State 5 of California, have invented certain new and useful Improvements in Closures for Receptacles, of which the following is a specification.

My invention relates to closures for receptacles such as jars and cans, and more particularly to a clamp for holding a cover upon such a receptacle, either temporarily, as during the operation of the vacuum process of exhausting the receptacle, permanently after the vacuum process has been completed, or originally and permanently where the vacuum process is not employed.

The device can be applied to glass jars with glass covers or to glass jars and sheet-metal covers; and it consists of a metallic spring-clamp of peculiar construction and peculiar holding qualities, both as a new article of manufacture in itself and in combination with a receptacle and cover, to which it 25 is especially adapted.

Embodiments of my invention are shown in the accompanying drawings, in which—

Figure 1 is a vertical section of a glass jar with sheet-metal cover and provided with 30 my improved clamp. Fig. 2 shows another form of jar and cover held together by the same clamp. Fig. 3 is a separate view of the clamp. Fig. 4 shows a clamp with curved arms instead of obtuse angular arms. Fig. 35 5 shows a clamp with straight cross-bar bent to form continuations and hooks according to my invention. Fig. 6 shows a slightly-different form of jar.

In Fig. 1 the jar 1 is provided with a projecting flange 2, which at the top forms a ledge 3, so that a gasket 4 may be compressed between such ledge and the cover. The lower side of this flange forms a shoulder 5. The cover in Fig. 1 is supposed to be of sheet 45 metal and is stamped or pressed with a top panel or flat depression bounded by a circular bead 6, and is also formed with a double flange or rim 7 8, separated by a flat seat 9, which when the cover is in place comes opposite and above the ledge 3. The double flange fits outside the upper or final rim of the jar

and also outside the flange 2. The closure shown in Fig. 2 is substantially the same, excepting that the cover is made with a single flange, the edge of which bears above the ledge 3. This form is more suitable for glass covers than for sheet-metal ones, although both materials can be used. Further, although this is not specially illustrated, the cover, whether of glass or metal, can be formed 55 without the depressed panel at the top, since the holding qualities of the clamp to be described do not depend upon such a depression in the cover.

The clamp is composed of spring metal and 60 is of peculiar shape. In reality there are two clamps, and although they are formed as a matter of convenience in one piece, with a connecting bar or strip 12, such strip performs no clamping function. The shape of the 65 clamp is well illustrated in Fig. 3. Each end of the bar is bent downward to form the obtuse angle 13 and the end is bent inwardly and preferably somewhat upwardly, as shown at 14. The obtuse angle 13 might, however, 70 be a curve, Fig. 4, as will be apparent when the operation is described. In no case, however, can the fall of the clamp from the upper edge of the cover be a straight line, a curve or an angle being necessary for the purposes 75 to be hereinafter described. Generally the connecting-bar 12 has an angle 15 and is rounded at 16 to pass over the edge, as shown. This angle is not essential, but with beaded covers it forms a point of contact between the 80 clamp and the top of the cover, the rounded portion 16 enabling the clamps to clear such beads, the angle 15 coming inside and bearing at about the junction of the bead and the main flat part of the cover. With covers not 85 beaded this raised portion can be omitted, Fig. 5. When the clamp is being placed in position, the advantage of the external obtuse angle or equivalent curve will at once be apparent. As the cover is to be held very tightly 90 and as a gasket is ordinarily used, the fitting is so close in order to obtain the positive spring-clamp action that a clamp which is straight outside the cover can only with the greatest difficulty be placed in position by 95 hand, because it fits closely against the outside of the jar and cover. When my clamp, 100

flexed or curved outside the jar, is to be placed in position, there is enough yield at the angle or curve to respond to pressure, and hence the hooked end can be forced under the lower corner of the flange by pressure upon such angle, Fig. 6. After the engagement the rigidity is the same as that of a straight-turned clamp. When the clamp is in place, the connecting-bar 12 need not fit the cover nor even be in contact therewith. In fact, the cover might be concave and the bar 12 straight or even convex. As a part of the actual clamp the function of the bar 12 is only a means of connecting the two clamps and enabling them to be applied at the same time. The clamps remain permanently in position unless forcibly removed, which can be done by prying out one end with any suitable implement.

My invention provides a clamp for holding the covers on receptacles which will be economical to construct and easy to operate and will also exert an exceedingly powerful pressure. The clamp is formed of stiff spring metal bent so as to form a plain cross-bar with extensions in obtuse angular or equivalent curved form, which not only permit the clamp to adjust itself to any irregularities in the shape of the glass, but also furnishes the means for easily springing or snapping the clamp into place. The short extent of the angular or curved extensions gives great power to the clamp without impairing their inherent advantages, hereinbefore fully set forth.

It will be noticed that my invention includes, in effect, two bow-shaped clamping devices at the opposite sides of the cover, which are connected by a cross-bar. These bow-shaped portions have their lower ends engaging the receptacle and at their upper ends or where they join the cross-bar they engage the cover. The bow-shaped portions included

in some of the forms show elevated portions to pass over the bead of the cover.

Having thus fully described my invention, what I claim as new, and desire to obtain by Letters Patent, is—

1. A clamp for covers of receptacles comprising a bar, hooks to engage a portion of the receptacle and bow-shaped connections between the said hooks and the ends of the bar, substantially as described.

2. A clamp for covers of receptacles comprising a bar having at its ends outwardly-bowed continuations which engage above and below respectively the cover and a part of the receptacle, substantially as described.

3. A clamp for covers of receptacles comprising a bar having at its ends outwardly-bowed continuations having hooks at their extremities engaging a part of the receptacle, substantially as described.

4. A clamp for covers of receptacles comprising a bar having a clamping portion at each end, each clamping portion or member comprising a hook to engage a part of the receptacle, a portion to engage the cover and an intermediate outwardly-bowed portion, substantially as described.

5. In combination with a receptacle having a projection, a cover and a clamp comprising a bar having outwardly-bowed-shaped portions at its ends ending in hooks, the upper ends of the bowed parts pressing on the cover, substantially as described.

In testimony whereof I have affixed my signature, in presence of two witnesses, this 4th day of October, 1902.

JULIUS A. LANDSBERGER.
